UNITED STATES PATENT OFFICE.

WILLIAM S. FILLEY, OF MONTPELIER, OHIO.

CARBURETER.

SPECIFICATION forming part of Letters Patent No. 620,646, dated March 7, 1899.

Application filed February 17, 1898. Serial No. 670,667. (No model.)

To all whom it may concern:

Be it known that I, WILLIAM S. FILLEY, a citizen of the United States, and a resident of Montpelier, in the county of Williams and 5 State of Ohio, have invented certain new and useful Improvements in Carbureting-Machines; and I do hereby declare that the following is a full, clear, and exact description of the invention, which will enable others 10 skilled in the art to which it appertains to make and use the same, reference being had to the accompanying drawings, which form a part of this specification.

My invention relates to machines for carbureting air by forcing the same through gasoline or other liquid hydrocarbon, whereby it becomes saturated with the inflammable vapors of the hydrocarbon, so that it may be burned for heating or lighting purposes.

20 The object of the invention is to provide a machine for the above purpose which shall be simple and economical in construction and which shall possess superior advantages with respect to efficiency in use.

25 The invention consists in the novel construction and combination of parts hereinafter fully described and claimed.

In the accompanying drawings, Figure 1 is a central longitudinal section of a carbureting-machine constructed in accordance with 30 my invention. Fig. 2 is a detail view of the mechanism for operating the valves of the hydraulic cylinder.

In the said drawings the reference-numeral 35 1 designates a cylindrical water-tank open at the top and closed at the bottom and supported by legs 2. Telescoping or fitting in said tank is a vertically-movable tank 3, provided with a cover 4 at the upper end and 40 open at the lower end. There is an air-opening 5 in said cover provided with an inwardly-opening flap-valve 6. Secured to the said tank 1 by brackets 7 is a hydraulic cylinder 8, in which works a vertical plunger 9, the 45 upper end of which is provided with a lateral arm 10, secured to the cover of tank 3. At the lower end said cylinder is provided with water supply and outlet pipes 12 and 13, provided with valves 14 and 15. The arm 16 of 50 valve 14 is connected with a vertically-movable rod 17, provided with upper and lower lugs 18 and 19, adapted to be alternately en-

gaged by a lug 20 on the cover of tank 3. The rod 17 is also connected with a lever 21, pivoted to the cylinder 8, the opposite end of 55 which is connected by a link 23 with the arm 24 of valve 15. The rod 17 passes through guides 25, secured to tank 1.

The numeral 26 designates a tank for containing gasoline or other liquid hydrocarbon. 60 Located in the lower part of said tank 26 is a horizontal pipe 27, provided with a number of perforations and connected with a valve-box 28, located below the box and provided with a check-valve 29. Connected with said 65 valve-box below the valve is a pipe 30, leading up into a supplemental air-tank 31. Connected with said box above the valve is a pipe 32, provided with a check-valve 34. This pipe 32 is connected with a pipe 35, extending up into tank 1, above the water-level 70 therein. At the upper end of said tank 26 is an escape-pipe 36, provided with a valve 37, which valve is connected with a lever 38, provided with a number of notches 39, with which 75 is connected a weight 40. This lever is pivoted to a stand 41 and is provided with a rod 42, connected with a valve 43, located in a casing 45. This casing and the casing of valve 37 are connected by a pipe 46. The 80 valves 37 and 43 serve as regulating-valves for automatically regulating the pressure in the burner-pipe.

Telescoping in the supplemental air-tank 31 is a vertically-movable cylinder 47 for the 85 purpose of keeping up a supply of air in the gasoline-tank while the cylinder or tank 3 is moving upward and the air-pressure therein consequently relieved. The tank 31 is provided with a pipe 48, leading up into tank 90 3. The numeral 49 designates a check-valve in said pipe.

The numeral 50 designates the burner-pipe, connected with the casing 45 of valve 43.

The operation is as follows: The tank 1 is 95 filled nearly to the top with water and the supply-valve 12 opened to allow water to enter the hydraulic cylinder, elevating the plunger and raising tank 3. The valve in the top of said tank will open as said tank rises to 100 allow air to enter. When said tank has reached the limit of its upward movement, the lug 20 will strike the lug 19 of rod 17 and through the connections will close valve 12

and open valve 13. The air in said tank will now be compressed, valve 6 closing, and will be forced to the gasoline-tank. For the purpose of keeping up the pressure in the gasoline-tank while said tank 3 is rising, which will relieve the air-pressure in the latter, I provide the tanks or cylinders 31 and 47. As the tank 3 falls air will be forced into tank 31, elevating tank or cylinder 47; but when said tank 3 rises to renew the air-supply check-valve 49 will close, so that the compressed air in said tanks 31 and 47 will be forced through the gasoline-tank.

Should the pressure in the burner-pipe be come too great or above a predetermined limit, the valve 43 will be forced upward, overcoming the resistance of the weight and depressing the valve 37, so as to partially close the latter and then reducing the amount of carbureted air admitted to the burner-pipe.

Having thus fully described my invention, what I claim is—

1. In an air-carbureting machine, the combination with the air-tank and means for supplying it with air, the hydrocarbon-tank, the pipe extending up into said air-tank, the pipe connected therewith and with the hydrocarbon-tank provided with a check-valve, the horizontal perforated pipe in said hydrocarbon-tank, the escape-pipe at the upper end of said hydrocarbon-tank provided with a check-valve, the lever connected therewith

provided with a weight, the reducing-valve and the burner-pipe, of the supplemental air-tank, the pipe connected therewith and extending up into the same, the check-valve therein and the pipe connected with said supplemental tank and with the hydrocarbon-tank, substantially as described. 35

2. In an air-carbureting machine, the combination with the air-tank and means for supplying air thereto, the hydrocarbon-tank having the valve-box connected with the lower end thereof, the check-valve therein, the pipe connected with said valve-box above the valve therein, the pipe connected therewith extending up into the air-tank and provided with a check-valve, and the perforated pipe located in said hydrocarbon-tank and connected with said valve-box, of the supplemental air-tank, the pipe connected therewith and extending up into said air-tank, the check-valve therein, and the pipe connected with said supplemental air-tank and with said valve-box below the valve therein, substantially as described. 40 45 50 55

In testimony that I claim the foregoing as my own I have hereunto affixed my signature in presence of two witnesses.

WILLIAM S. FILLEY.
